UNITED STATES PATENT OFFICE.

JESSIE B. WHITE, OF PROVIDENCE, RHODE ISLAND.

FASTENER DEVICE.

Application filed February 16, 1922. Serial No. 536,991.

To all whom it may concern:

Be it known that I, JESSIE B. WHITE, a citizen of the United States, residing at Providence, in the county of Providence, and 5 State of Rhode Island, have invented certain new and useful Improvements in Fastener Devices, of which the following is a specification.

The invention has for an object to provide 10 new and novel means of a satisfactory character for suspending articles from doors, partitions, et cetera, without requiring permanent fixture attachment, and without marring the surface of the structure. It is 15 an important aim of the invention to provide such a device which will be useful to traveling people, particularly, enabling them to hang objects upon doors of closets, or the doors of rooms, so that a kit of appliances 20 or apparel may be hung in a convenient location for use, without requiring them to be spread about, or distributed in drawers of dressing room furniture. It is a particular aim of the invention to provide such a device 25 which may be used without interfering with the closing of a door upon which it may be employed, and which will yet be amply strong and positive in its engagement with the door to afford a safe support for objects 30 of considerable weight. It will thus dispense with the necessity of using screws, tacks, or the like, and in case of special articles, and devices requiring more than one supporting element, the supports may be 35 readily adjusted in proper spaced relation to permit the ready handling of such articles.

The device is also useful as a permanent attachment, as it will be less likely to fail 40 than tacks, nails, and screws of the ordinary type used for supporting articles upon doors.

Additional objects, advantages and features of invention reside in the particular construction of device embodying my invention, and in the relation of the parts thereof 45 to each other and to an object with which the device may be engaged.

In the drawings,

Figure 1 is a perspective view of a closet 50 door upon which a multiple pocket device is

hung by means of hangers embodying my invention,

Fig. 2 is a detail perspective view of one of the hangers, as viewed from above,

Fig. 3 is a front elevational view of the 55 hanger,

Fig. 4 is a side view thereof,

Fig. 5 is a top view of the device applied to a door,

Fig. 6 is a perspective view of another 60 form of hanger device in which the spring is formed separate and subsequently connected to one of the arms thereof,

Fig. 7 is a perspective view of my device 65 formed of wire.

There is illustrated a door 10, in the present instance shown as a closet door, although my device may be applied with equal facility to various doors. Upon the upper edge of the door there are engaged 70 hanger clamps 11, a multiple pocket holder or container 12 for slippers or other articles being suspended therefrom, although various other objects or articles may be suspended from the hangers 11. The container 12 is of 75 a character which is adapted to be readily rolled up and disposed in a suit case or trunk, and includes a back piece 13, upon which the pockets 14 are sewed. At the upper corners of the back 13, there are attached 80 loops 15, which are engaged in hooks 16 formed upon the lower parts of the hangers 11. This attachment of the loops 15 to the hangers may be permanent, if desired by turning the hook element 16 inwardly so as 85 to close over the loop 15, or the hooks may be left sufficiently open to receive the loop.

The hanger devices 11 are preferably each stamped from resilient sheet material, and in some cases are formed integrally from 90 one blank. Each hanger comprises a body portion 17 broadened medially as at 18 (though this is not essential), with its opposite end portions bent into planes at right angles to each other on a line transversely 95 of the broadened part, and if desired, the central portion may be cut away to save material and lighten the device. One lower portion of the body may be extended as at 19 and recurved to form a hook 16 or eye 100

20, as shown in Fig. 4, or other support or devices, while the opposite end portion is extended downwardly parallel to the part 19, as shown at 22 in Figs. 2, 3, and 4, and 5 from this downwardly extending part, lateral arms 23 are extended at each side curved inwardly, and broadened and turned outwardly slightly at their ends, forming leaf springs by which the device may be caused 10 to grip and so retained upon a door, as shown in Fig. 5. If desired, one or both of the lower parts of the body may be shaped to provide various useful devices.

15 The arms 23 may be slightly attenuated at their medial portions, in order to attain proper flexure. The extremities of the arms are also extended downwardly and turned outwardly as at 24, which permits these ends to be adjusted upon the door or other support 20 without marring the surface.

25 In putting the hangers in place, one is grasped by the lower part 19 and adjusted over the top edge of the door which is to serve as a support. The ends of the arms 23 are adjusted against the face of the door opposite the jamb, with the angle in the broad part 18 disposed medially over the door. A downward pull on the hook end of 30 the hanger then will cause the part 19 to slide into place against the inner face of the door, or that next to the jamb, the arms 23 yielding sufficiently and easily by this operation to accommodate the hanger to the thickness of the door. The arms 23 will also 35 slide downward at the same time, so that the portion 17 of the device will rest snugly upon the top edge of the door. The two or more hangers being thus engaged and the article to be suspended being in place, the 40 door may then be easily closed without interference, or obstruction.

45 In practice, the device has been formed of sheet metal one thirty second of an inch in thickness, the span of the arms 23 being about four inches, and the part 17 measuring about two inches between bends. Other materials may be used, however.

50 In Figures 1 to 5, I have shown the hook blank as formed from a single piece of sheet stock but in some instances, as illustrated in Fig. 6, the spring gripping arm members may be formed separately and independent of the body portion of the hook member and connected thereto by any suitable 55 means. In one instance, a portion of the stock of the front or back may be forced inwardly as at 25 in Fig. 6, forming a loop through which the separate spring arm 26 may be passed and secured. This also permits the body of the stock to be formed of strap stock, or simple blanks cut, with practically no waste, for the particular form 60 shown.

One advantage in forming the spring

65 member separate from the body member is that the spring member may then be made of spring stock while the rest of the body portion may be formed of a more ductile metal which has no spring temper. Then again by forming the spring arm separate 70 and independent of the body portion of the hook, the stock wasted in the operation is reduced to the minimum. The body with the spring inserted as in Fig. 6 may have the form shown in Figs. 1 to 5, if desired. 75

In Fig. 6 the hanger is formed with a hook on both of its vertical arms so as to suspend articles therefrom on both sides of the door, or other support.

I have described this hook as being 80 formed of sheet metal, but I do not wish to be limited to forming the same of sheet stock as in some instances a length of wire may be folded into the desired shape to perform substantially the same function, as 85 indicated in Fig. 7. In this case, a single piece of wire is bent to form a bight 30 with its opposite portions extended in parallel relation a distance, the parallel parts are commonly bent to form a hook 31 of which the 90 bight 30 forms the bill with shanks 32 extending vertically. The wires are then bent backwardly at right angles to form top bars 33, then bent downwardly parallel to the shanks 32 forming back bars 34. The end 95 portions are then bent outwardly in opposite directions, but inclined toward the plane of the shanks 32 formed spring arms 35, and then curved backwardly and each formed with an eye 36, to prevent abrasion 100 of doors or for other purposes; or otherwise shaped for any desired purpose of utility. The top bars may be flattened as far as desired to permit use on doors which must be closed. It may be desirable to flatten the 105 wire included in the angle at the junction of the top bars 33 and also the upper portions of the shanks 32.

The foregoing description is directed solely towards the constructions illustrated, but 110 I desire it to be understood that I reserve the privilege of resorting to all the mechanical changes to which the device is susceptible, the invention being defined and limited only by the terms of the appended 115 claims.

What is claimed:—

1. As an improved article of manufacture, an article hanger for doors, comprising a sheet metal body bent sharply at right 120 angles at two lines spaced a distance much greater than the thickness of doors to be engaged and shaped to provide a thin flat cross plate and substantially parallel spaced door receiving members, one being very thin 125 and flat and having an article supporting means at its lower end, and a bow spring member transversely disposed on the other

of said members to grip a door, its arms extending laterally a considerable distance, and also extending partly across the space between said members, whereby to engage and accommodate doors of various thicknesses.

2. A device as specified in claim 1 in which the extremities of said spring are extended downwardly and bent outwardly

on a curve at an angle to the arms of the 10 spring, whereby the method of application described may be followed.

In testimony whereof I have affixed my signature in presence of two witnesses.

JESSIE B. WHITE.
